(57) **CLAIM**

The ornamental design for a firearm sling attachment point, as shown and described.

DESCRIPTION

FIG. 1 is a front view of a firearm sling attachment point in accordance with an embodiment of the invention;

FIG. 2 is a rear view of a firearm sling attachment point as shown in FIG. 1;

FIG. 3 is a left side view of a firearm sling attachment point as shown in FIG. 1;

FIG. 4 is a right side view of a firearm sling attachment point as shown in FIG. 1;

FIG. 5 is a top view of a firearm sling attachment point as shown in FIG. 1;

FIG. 6 is a bottom view of a firearm sling attachment point as shown in FIG. 1;

FIG. 7 is a regular isometric view of a firearm sling attachment point as shown in FIG. 1;

FIG. 8 is a reverse isometric view of a firearm sling attachment point as shown in FIG. 1; and,

FIG. 9 is an auxiliary angled side view of a firearm sling attachment point as shown in FIG. 1.
